UNITED STATES PATENT OFFICE.

WILLIAM F. KIESEL, JR., OF ALTOONA, PENNSYLVANIA.

LOCOMOTIVE.

1,416,718.

Specification of Letters Patent. Patented May 23, 1922.

Application filed February 5, 1920. Serial No. 356,387.

To all whom it may concern:

Be it known that I, WILLIAM F. KIESEL, Jr., a citizen of the United States, residing at Altoona, in the county of Blair, State of 5 Pennsylvania, have invented certain new and useful Improvements in Locomotives, of which the following is a specification.

The present invention relates to locomotives and more particularly to the connection 10 between the frames or units of an articulated locomotive.

The principal objects of the invention are to provide an improved pivotal connection between the adjacent ends of the frames or 15 units of an articulated locomotive; and to provide an improved construction of the swinging unit of such a locomotive, whereby the pivotal connection between the frames may be simplified and located so as to be 20 more accessible than heretofore.

In locomotives of the articulated type comprising two engines or units, each having 8 driving wheels, heretofore it has been difficult if not impossible to locate the pivot 25 between the units where it theoretically belongs. The best that can be done is to locate the same considerably in rear of the front frame, that is, inside of the saddle of the rear engine. Theoretically the location of 30 the pivot point is determined by the intersection of the center lines of the front and rear units. At present because the pivotal point is located well in rear of the front frame, the structure for connecting the units 35 comprises a triangular or three point connecting link, which has a vertical pin connection at one apex with the rear unit and two bearings on a horizontal shaft attached to the rear end of the front frame.

According to the present invention the second and fourth pairs of wheels or the fourth pair of wheels on the front unit have no flanges, while the first and fourth pairs or all the pairs of the rear unit have 45 flanges. As a result of this construction it is possible to locate the pivot connecting the frames where it theoretically belongs, as said pivot comes in front of the rear saddle.

Other objects and features of novelty will 50 be apparent from the description taken in connection with the drawings, in which—

Figure 1 is a top plan view of a locomotive, more or less diagrammatic, illustrating the frames and the pivotal connection 55 constructed in accordance with the present

invention. The outline of the boiler is shown in dot and dash lines;

Figure 2 is a side elevation of the parts shown in Fig. 1;

Figure 3 is a top plan view to a larger 60 scale of the universal pivotal connection between the frames, parts of the saddle of the rear frame being shown in section, and

Figure 4 is a sectional elevation taken substantially on line 4—4 of Fig. 3. 65

Referring to the drawings it will be seen that the present invention is illustrated in connection with a locomotive having two frames or units, the rear frame at its forward end being connected by means of a 70 pivotal joint to the rear end of the forward frame, said joint being in front of the rear saddle. As shown, the forward frame comprises the side bars 10 and 11 joined at their front ends to the saddle 12 of the 75 front engine, the cylinders being shown at 13 and 14. At the rear ends of the bars 10 and 11 is a transverse brace or cross member 15.

The rear frame may comprise the side 80 members 16 and 17 joined at their forward ends to the saddle 18 of the rear engine, the cylinders of this engine being shown at 19 and 20. The locomotive boiler is rigidly connected with the rear frame in any suitable manner, one of the connections being shown at 21. The front frame is adapted to swing relative to the boiler, a suitable sliding support as at 22 being provided. 85

The unit or engine which is adapted to 90 swing relative to the boiler, that is in the present instance the front unit, does not have flanges on all the driving wheels. As shown, the first and third pairs of driving wheels 10^b have the usual flanges while the 95 second and fourth pairs 10^a have no flanges. The rear unit which is rigid with the boiler is shown as having flanged driving wheels 16^b on the first and fourth pairs, while the flanges are omitted from the second and 100 third pairs 16^a. It is to be understood however that the rear engine may have flanges on other pairs of wheels in addition to the first and fourth pairs, and the front engine may have flanges on all wheels, except on the 105 pair adjacent to the rigid unit. Because of the omission of flanges, as mentioned above, on the front unit the theoretical point for the pivot joining the front and rear units comes in front of the rear saddle, in- 11

stead of inside said saddle as is the case where all the wheels of the front unit have flanges. Because of this location of the pivot it is possible to provide a much more simplified and more accessible connection between the units. From an inspection of Figures 1 and 2, it will be seen that the pivot connecting the units is at a distance from the axis of the adjacent drivers approximately equal to that of the radius of said drivers. Of course, the exact location of the pivot will vary with the size and number of drivers in the unit, but its location may be approximately defined as stated above.

According to the present invention one of the adjacent ends of the frames is provided with an extension which co-operates with arms on the other frame to support the universal joint or connection securing the frames together. In the form of the invention shown the saddle 18 of the rear engine is provided with an extension 23 projecting toward the other frame. This extension is formed with a vertical aperture 24 with a shoulder 25 at the bottom thereof. Preferably this aperture is circular. A pair of blocks 26 and 27 are disposed in the aperture 24, the lower peripheral edge of the lower block being formed with a rabbetted seat 28 resting on the shoulder 25. The top and bottom surfaces of the blocks are flush with the corresponding surfaces of the extension 23. In order to hold the blocks in position and together suitable bolts 29 are provided.

The blocks 26 and 27 taken together have their interior surfaces shaped to form a substantially spherical seat 30, and a substantially spherical member 31 is carried on this seat.

The cross member 15 of the front frame is provided with a pair of spaced arms 32 and 33 straddling the extension 23. A pin 34 extends through the arms and the spherical member 31, suitable bushings 35 and 36 being provided in the arms for the pin, if desired. The pin is held against longitudinal movement and to this end is provided with a head 37 at its lower end which prevents movement in one direction, that is, upward. Movement in the downward direction is prevented by the bolt 38 extending transversely to the pin and bearing against the lower surface of the head 37. In order to permit slight vertical rocking movements of the frames the distance between the adjacent faces of the arms 32 and 33 is slightly greater than the height of the extension 23.

For the purpose of lubricating the bearings, the pin 34 is provided with an axial hole 39 extending downward from its upper end to a point below the upper surface of the extension 23. At its upper end this axial hole is enlarged to provide a cavity for a lubricant carrying packing or other material

40. In the plane substantially between the upper surface of the extension 23 and the lower surface of the arm 32 the pin is formed with the radially extending oil ducts 41 whereby the lubricant is carried to the bearing surfaces between the pin and the spherical member and also between the spherical member and its seat.

In operation the front frame may swing in a horizontal direction considerably with respect to the rear frame. In this movement the pin 34 in the arms and the spherical member, constitutes the pivot. For rocking movements in any other direction the spherical member 31 carried by the pin moves in its seat in the blocks 26 and 27. Furthermore because the flanges are omitted from the fourth pair of wheels of the front unit, the pivotal connection between the frames may be located in front of the rear frame and secured directly thereto, thereby affording a stronger, simpler and more accessible connection.

Although an embodiment of the invention has been described in detail it is to be understood that the invention is not thus limited, but includes modifications and changes which come within the scope of the appended claims.

Having thus described my invention what I claim is:

1. In a locomotive, a front frame, a rear frame, one of said frames being rigid with the boiler and the other adapted to swing laterally thereof and means pivotally connecting said frames end to end, said pivot being in front of the rear frame and at a distance from the axis of the adjacent drivers approximately equal to the radius of said drivers.

2. In a locomotive, a front frame, a rear frame, one of said frames being rigid with the boiler and the other adapted to swing laterally thereof and a universal pivotal connection directly securing the front of the rear frame to the rear of the front frame whereby the non-rigid frame may swing in any direction relative to the rigid frame, the pivot being in front of the rear frame and at a distance from the axis of the adjacent drivers approximately equal to the radius of said drivers.

3. In a locomotive, a front frame, a rear frame, one of said frames being rigid with the boiler, and the other non-rigid, a substantially spherical seat in front of the front end of the rear frame, a spherical member carried on said seat and means securing the adjacent end of the other frame to said member.

4. In a locomotive, two frames, one being rigid with the boiler and the other adapted to swing laterally thereof, an extension at the front end of the rear frame having a substantially spherical seat, a substantially

- spherical member fitted to said seat and a pin passing through said member and secured to the adjacent end of the front frame.
5. In a locomotive, two frames, one being rigid with the boiler and the other adapted to swing laterally thereof, a rigid extension at the end of one frame projecting toward the other frame, a spherical member seated in said projection, said other frame having two arms straddling said projection and a pin carried by said arms and extending through said member.
10. In a locomotive, two frames, one being rigid with the boiler and the other adapted to swing laterally thereof, an extension at the front end of the rear frame, and means pivotally connecting said extension to the rear end of the front frame said pivot being disposed at a distance from the axis of the adjacent drivers approximately equal to the radius of said drivers.
15. In a locomotive, two frames, one being rigid with the boiler and the other adapted to swing laterally thereof, a rigid extension at one end of one frame projecting toward the other frame, said other frame having a pair of arms straddling said extension, and a vertically disposed pin connecting said arms and extension said pin being located at a distance from the axis of the adjacent drivers substantially equal to the radius of said drivers.
20. In a locomotive, two frames, the rear being rigid with the boiler and the front frame adapted to swing laterally thereof, a rigid extension at the front end of the rear frame projecting toward the front frame, said front frame having a pair of arms straddling said extension, and a vertically disposed pin connecting said arms and extension said pin being located at a distance from the axis of the adjacent drivers approximately equal to the radius of said drivers.
25. In a locomotive, two units, each including four pairs of driving wheels, the first and third pairs of the front unit being flanged and the second and fourth pairs having smooth peripheries, and a pivotal connection securing said units end to end, said connection being in front of the rear unit.
30. In a locomotive, two units, each including four pairs of driving wheels, alternate pairs of the front unit having no flanges, and a pivotal connection securing said units end to end, said connection being in front of the rear unit.
35. In a locomotive, two units, each including four pairs of driving wheels, one unit being rigid with the boiler, and the other adapted to swing relative thereto, the latter unit having no flanges on alternate pairs of wheels, and a pivotal connection securing said units end to end, said connection being disposed in advance of the end of the unit rigid with the boiler.
40. In a locomotive, two units, each including four pairs of driving wheels, one unit being rigid with the boiler and the other adapted to swing relative thereto, the latter unit having no flanges on the pair of wheels adjacent the rigid unit, and a pivotal connection securing said units end to end, said connection being disposed in advance of the rigid unit.
45. In a locomotive, two units, each including four pairs of driving wheels, the rear unit being rigid with the boiler and the front unit adapted to swing relative thereto, the front unit having no flanges on its rear pair of wheels, and a pivotal connection securing said units end to end, said connection being disposed in front of the rear unit.
50. In a locomotive, two units, each including four pairs of driving wheels, the first and third pairs of the front unit being flanged and the second and fourth pairs having smooth peripheries, and a pivotal connection securing said units end to end, said connection being in front of the rear unit.
55. In a locomotive, two units, each including four pairs of driving wheels, alternate pairs of the front unit having no flanges, and a pivotal connection securing said units end to end, said connection being in front of the rear unit.
60. In a locomotive, two units, each including four pairs of driving wheels, one unit being rigid with the boiler, and the other adapted to swing relative thereto, the latter unit having no flanges on alternate pairs of wheels, and a pivotal connection securing said units end to end, said connection being disposed in advance of the end of the unit rigid with the boiler.
65. In a locomotive, two units, each including four pairs of driving wheels, one unit being rigid with the boiler and the other adapted to swing relative thereto, the latter unit having no flanges on the pair of wheels adjacent the rigid unit, and a pivotal connection securing said units end to end, said connection being disposed in advance of the rigid unit.
70. In a locomotive, two units, each including four pairs of driving wheels, the rear unit being rigid with the boiler and the front unit adapted to swing relative thereto, the front unit having no flanges on its rear pair of wheels, and a pivotal connection securing said units end to end, said connection being disposed in front of the rear unit.
75. In a locomotive, two units, each including four pairs of driving wheels, the first and third pairs of the front unit being flanged and the second and fourth pairs having smooth peripheries, and a pivotal connection securing said units end to end, said connection being in front of the rear unit.

In testimony whereof I affix my signature.
WILLIAM F. KIESEL, JR.
